UNITED STATES PATENT OFFICE

JAMES ALFRED HALL, OF BEDFORD, AND WALTER FRANK CROSS GEORGE, OF WILBY,
ENGLAND

GRAIN-CONDITIONING MACHINE

Application filed October 15, 1928, Serial No. 312,724, and in Great Britain July 26, 1928.

This invention relates to grain conditioning machines of the type in which the grain as it descends the tower or casing of the machine intermingles with air which is caused to flow across the tower by means of inverted ducts or troughs arranged in rows or tiers so that air entering the ducts in one tier must pass into the stream of descending grain and intermingle therewith before it can flow out by way of the ducts in another tier.

With such machines, it is found in practice that under certain conditions there is a tendency for fine material carried by the air leaving the grain to deposit in the exhaust ducts in the tower or casing and also in the exhaust trunks and conduits outside such tower or casing, and such deposits restrict the passageways for the withdrawal of air and may rapidly block some or all of the same entirely.

The object of our present invention is to provide in a simple and effective manner for the prevention of the accumulation of deposited material in the exhaust ducts and trunks or conduits of a grain conditioning machine and it comprises essentially the introduction into the exhaust ducts in the grain tower or casing and also, if necessary, into the exhaust trunks or conduits leading from said ducts, of hot air which has not passed through the grain, whereby we prevent the deposition of moisture in said ducts and conduits due to condensation of the vapours carried by the air from the grain and the consequent accumulation of light material which adheres to the wetted surfaces and builds up thereon.

Our invention further comprises the bypassing of a portion of the hot air passing into the air inlet ducts of the grain tower or casing, directly into the exhaust conduits on the outside of such casing.

Our invention further comprises the provision of a blank section through which no air is circulated between the upper portion of the tower or casing through which hot air is circulated and the lower portion of such tower or casing through which relatively cold air is circulated, said blank section preventing the passage of cold air into the exhaustion

ducts of the upper portion of the tower or casing and so obviating the cooling of the air in such ducts and the deposition of moisture therein.

Referring to the accompanying explanatory drawings:

Figure 1 is a diagrammatic view of a grain conditioning machine constructed in accordance with this invention.

Figure 2 is a sectional front elevation, Figure 3 a side elevation looking from left to right of Figure 2, but with a part of the exhaust trunk or conduit broken away for the sake of clearness, and Figure 4 a sectional plan view on the line AB of Figure 3, showing diagrammatically the details of the machine illustrated in Figure 1.

The same reference letters in the different views indicate the same parts.

The machine comprises a tower or casing *a* into the top of which grain is fed at *b* and from the bottom of which the grain is withdrawn at *c*. There are the usual control fittings (not shown) at *b* and *c*.

Across the tower or casing *a* extend a number of rows of inverted troughs or ducts *d*, *e* and *f*, *g*. Such ducts are open at the bottom and closed at the top. There is a space between the superposed rows of ducts and also a space between the several ducts in each row. The ducts in one row are not in line with the ducts in the rows above and beneath so that the grain in descending the tower has its path diverted and the stream broken up to ensure an efficient action of the air currents on the grain.

At one side of the tower or casing *a* is a hot air inlet conduit *h* and at the opposite side an air exhaustion conduit *i* which leads by way of a pipe *j* to a fan *m* and an air heater *n* and so back to the hot air inlet conduit *h*. The latter is in free communication with the ducts *e* in alternate rows of ducts across the tower or casing and the exhaust conduit *i* is in free communication with the ducts *d* which alternate with *e*. If desired, a portion of the air from the conduit *i* may be bypassed into the exhaust conduit *o* by way of the passage *j'* controlled by a suitable valve.

At the lower part of the tower or casing

are the rows of ducts *f*, *g*, the alternate rows *f* communicating freely with the exhaust conduit *o* which leads to the fan *p* and dust separator *q* and so to the atmosphere, whilst the alternate rows *g* are open at one end to the atmosphere so that cool air from the atmosphere is drawn through the grain before it is discharged from the tower.

It will be understood that the hot air entering by the conduit *h* passes into the ducts *e*, out through the open lower ends of same, and through the descending grain to the ducts *d*, which it enters at their open lower ends and so passes to the exhaust conduit *i* to be reheated in *n* and returned to the ducts *h*.

In accordance with our present invention, we provide each air outlet or exhaust duct *d* with one or more small apertures *r* at the end opposite to that at which the air exhaustion conduit *i* is situated and cause hot air to pass through said apertures direct from the hot air supply conduit *h*. The admission of such hot air directly to the exhaust ducts *d* within the tower or casing *a* maintains a sufficiently high temperature in such ducts to prevent condensation of moisture therein which would by wetting the surface facilitate the deposit and accumulation of light or fine material withdrawn from the grain by the air.

Further, the air jets issuing from the apertures *r* into the ducts *d* act as boosters to speed up the delivery of any solid material from the ducts *d* into the exhaust conduit *i*.

In addition to the admission of hot air directly to the exhaust duct *d* within the grain tower or casing *a*, we may pass hot air from the hot air inlet conduit *h* to the exhaust air conduit *i* by a by-pass connection *s* having a valve *t* therein, in order to prevent condensation in the external pipe system leading from the ducts *d* through conduit *i*, and fan *m* to the heater *n*. A blank section *k* which has no air connections is disposed between the upper portion of the tower or casing to which hot air is supplied and the lower portion to which cold air is supplied, for the purpose of preventing the exhaustion means for the hot air drawing cold air from the lower portion of the tower, which would cause a deposition of moisture in the exhaustion conduits and ducts.

What we claim is:—

1. A grain conditioning machine comprising a tower or casing with an air inlet conduit extending down one side thereof and communicating freely with alternate rows of ducts open at their lower ends which extend across the grain tower or casing, an air exhaust conduit extending down the opposite side of the tower or casing and communicating freely with the other alternate rows of ducts which extend across the tower or casing, the exhaust conduit and the inlet conduit being in communication outside the tower or casing by means of a fan and heater, and

means establishing a restricted communication between the air inlet conduit and the alternate rows of exhaust ducts within the tower or casing, and a valve controlled communication on the outside of the tower or casing between the air inlet conduit and the exhaust conduit.

2. A grain conditioning machine comprising a tower or casing with an air inlet conduit communicating freely with alternate rows of ducts open at their lower ends which extend across the grain tower or casing, an air exhaust conduit communicating freely with the other alternate rows of ducts which extend across the tower or casing, and means establishing a restricted communication between the air inlet conduit and the alternate rows of exhaust ducts within the tower or casing.

3. A grain conditioning machine comprising a tower or casing with an air inlet communicating freely with alternate rows of ducts open at their lower ends which extend across the grain tower or casing, an air exhaust conduit communicating freely with the other alternate rows of ducts which extend across the tower or casing, means establishing a restricted communication between the air inlet conduit and the alternate rows of exhaust ducts within the tower or casing, and means establishing direct communication between the air inlet conduit and the air exhaust conduit.

4. A grain conditioning machine comprising a tower or casing, a plurality of rows of ducts open at their lower ends which extend across the upper part of said tower or casing, hot air inlet and exhaust conduits, alternate rows of such ducts communicating with said inlet and with said exhaust conduits, means establishing a restricted communication between the inlet conduit and the alternate rows of ducts which communicate with the exhaust conduit, and further rows of ducts open at their lower ends extending across the lower part of said tower or casing, but with a space above them with no ducts therein below the aforesaid inlet and exhaust ducts, the lower rows of ducts communicating alternately with the atmosphere and with exhaustion means.

In testimony whereof we have signed our names to this specification.

JAMES ALFRED HALL.

WALTER FRANK CROSS GEORGE.
